UNITED STATES PATENT OFFICE.

RUTH E. CHEW, OF BROOKLYN, NEW YORK.

WATERPROOF HAT-PROTECTOR.

1,337,506.

Specification of Letters Patent. Patented Apr. 20, 1920.

Application filed July 24, 1918. Serial No. 246,583.

To all whom it may concern:

Be it known that I, RUTH E. CHEW, a citizen of the United States of America, and a resident of Brooklyn, Kings county, and 5 State of New York, have invented certain new and useful Improvements in Waterproof Hat-Protectors, of which the following is a specification, reference being had to the accompanying drawings, forming a part 10 thereof.

My invention relates to hat protectors or head coverings and has special reference to such as are made of paper, cloth or other light, flexible material which may be readily 15 waterproofed and serve as a protection against rain and snow or dust.

I am aware that paper hat covers have been suggested prior to my invention, but hitherto they have been objectionable in various ways which have rendered them impracticable and have prevented their extensive use. For example, they have lacked any ready means for securing them in position without delay or danger of their being 25 blown away by the first strong gust of wind encountered. Furthermore, they have been unattractive in appearance, not easily adjustable to hats of varying kinds and sizes and not easy to manufacture.

These objections are overcome by my invention which has for one object to provide 30 an improved protector of the character above indicated, that shall be very attractive in appearance and embody simple and particularly effective means for securing the 35 protector to a hat.

A further object of my invention is to provide a protector having means which is not only adapted for fastening the protector 40 to a hat but is also arranged and intended for holding folds or plaits which may be introduced when the protector is used for hats of smaller size, or is utilized without a hat, as a motor cap or a dust cap.

While my improved protector may be made in a number of sizes and styles if desired, this is not necessary as each protector has the great advantage of being adaptable to various sizes and styles of hat 45 as well as different fields of usefulness, so that a uniform protector may be manufactured in large quantities at very small expense.

In order that my invention may be thoroughly understood, I will now proceed to 55 describe the same in the following specification, and will then point out the novel features thereof in appended claims.

Referring to the drawings:

Figure 1 is a side view of a hat to which 60 is applied a protector constituting one embodiment of my invention.

Fig. 2 is a bottom plan view of a portion 65 of the same hat and protector showing my improved fastening means.

Fig. 3 is a partial section of the hat and 70 protector showing the fastener on a larger scale.

Fig. 4 is a detail view of the protector with one of its fasteners.

Fig. 5 is a sectional detail on the line 5—5 of Fig. 4.

Fig. 6 shows the protector as cut out of a 75 piece of fabric before it is completed.

Fig. 7 is a view corresponding to Fig. 6, 80 of a modified form of protector with different fasteners, which also embody my invention.

Fig. 8 is an elevation illustrating the 85 protector of my invention as used for a motor or dust cap.

Fig. 9 is a sectional detail showing one of the tabs of Fig. 8 construction.

Referring to Figs. 1 to 6, the protector here shown is formed by cutting a sheet of 85 wax paper or other fabric in any suitable manner by a templet or pattern into the shape clearly indicated in Fig. 6. In general, the form is circular or elliptical but is provided with V-notches 10 forming front 90 and back portions 11 and sector-shaped side portions 12. The side and front portions are provided with tabs or ears 13 which are adapted to be folded under the brim of a hat as shown in Fig. 2, or to hold a plait as 95 shown in Figs. 8 and 9, or for both purposes.

The protector is provided at each tab or between tabs or both with flexible strips 14 which stiffen the tabs and constitute means 100 for securing the protector to the hat. For this purpose I prefer to use ribbon wire which consists of tape 15 to which is secured flexible wires 16, as shown in section in Fig. 5. This ribbon wire is secured to 105 the protector by stitching, gluing or some

other suitable means. The wire has the characteristic of maintaining the position to which it is adjusted and at the same time is flexible. Consequently, it serves as a particularly advantageous means for fastening the protector to the rim of the hat.

The sector-shaped side members 12 are overlapped and pasted to the end member 11. Tapes or strings 17 are secured to the tabs 13 in the middle of the side members 12. These tapes or strings may be made of ribbon or of ordinary cotton tape and they may be conveniently attached to the ends of the correspondingly located ribbon wires 14.

15 The protector is sufficiently large in size to cover an ordinary hat and may be large enough to cover even a large hat without difficulty. If the hat is large, the protector will fit more closely so that the tabs can be bent under the brim of the hat as shown in Fig. 2, the strings or ribbons 17 being tied at the back as shown in Fig. 1, or under the chin as desired.

If the hat is of moderate or small size, 25 plaits are folded into the protector as it is applied, the plaits being preferably formed at or near the tabs so that when the tabs with their flexible wires are bent to hold the hat in position, they also hold the plait.

30 Some of the tabs may be used solely for holding plaits while others may be used for securing the hat in position, if desired. The protector may be fulled in at the back or front by drawing the tapes or strings 17 as 35 shown in Fig. 1, the amount to be gathered in, varying with the size of the hat. The strings or tapes 17 may be omitted if desired, and the protector is adapted for use with men's hats as well as ladies' hats.

40 The advantages of the thin protector will be well understood, it being particularly adapted to be folded flat when not in use and carried in the pocket or hand satchel so that it is ready to be quickly applied to a 45 hat for protection, in case of a shower or other necessity. The protector may be utilized to keep the hat free from dust as well as to keep the hat dry.

The seams may be stitched as shown in 50 Fig. 4, but are preferably pasted or glued to make a water-tight joint whether they are sewed or not.

The protector of my invention is not limited for use with a large hat and may 55 quickly be plaited in or fulled to cover a small hat and may in fact be worn directly on the head as a motor cap or a dust cap. It is illustrated in this connection in Fig. 8. As here shown the side tabs to which the 60 tapes or strings 17 are attached are folded forwardly, the strings being tied in front to hold the fulled portion 26 of the protector and the other tabs are folded to hold the plaits as indicated at 20.

65 The wires in the front tend to hold this

portion of the protector stiff like a visor which thus serves as a shade or protector for the eyes of the wearer. The tapes may of course be tied under the chin if desired.

The hat protector may be originally shaped in different ways, another pattern being shown in Fig. 7 in which the protector is cut into two side members 21 with V-notches 22 at the front and back. The strings or tapes 23 are attached to the centers of the side members, and metal fasteners 24 are attached to the side pieces near the front and back by means of flexible cords or tapes 25. With this arrangement the fasteners 24 are flexible metal and correspond to the wires 16 of the fasteners 14. When the edge of the protector is bent under the rim of a hat it may be held in place by applying the fasteners. Similarly, if folds or plaits are to be made in the protector they may be held at the same time the protector is fastened to the hat by means of one of the metal fasteners 24.

Attention is particularly directed to the fact that the protector may very quickly be fastened in position on the hat and nevertheless the fastening means is very effective so that even a strong wind will not loosen or damage the protector in any way.

Devices of preferred form and construction have been illustrated and described for the purpose of showing ways in which this invention may be used, but the inventive thought upon which this application is based, is broader than these illustrative embodiments thereof, and I therefore intend no limitations other than those imposed by the appended claims.

What I claim is:

1. A hat protector comprising a water proof paper bag or cover shaped like a shallow receptacle or basin having a plurality of bendable metal strips affixed near its edges and extending at an angle relative thereto, and adapted to be bent into a clamping engagement with the brim of a hat so as to hold a portion of the rim of the protector under the brim of the hat, and securely affix the protector to the hat brim.

2. A hat or head protector comprising a paper cover having a plurality of tabs extending outwardly at its edges and a ribbon wire extending radially, secured to the protector at the tabs, and adapted to be bent under the hat brim to hold the protector in position.

3. A hat or head protector comprising a paper cover shaped like a shallow receptacle or basin and having a plurality of tabs at its edges, a ribbon wire extending radially and affixed to the cover at each tab and adapted to be bent back upon itself to clamp gathers or plaits into the cover and tie strings secured to one set of opposite tabs.

4. A hat or head protector comprising a

paper cover composed of a substantially circular shape provided with two-spaced V-notches at the front and back and seamed at the edges to produce a shallow receptacle
5 shape and flexible metal tapes, secured to the protector at the seams, extending radially relative to the protector and adapted to be

bent under the brim of a hat to hold the edges of the protector in a folded-under position and to clamp the protector to the hat. 10

In witness whereof I have hereunto set my hand this 9th day of July, 1918.

RUTH E. CHEW.
